UNITED STATES PATENT OFFICE.

AUGUSTUS L. DUWELIUS, OF CINCINNATI, OHIO.

ELECTRIC ELEVATOR.

SPECIFICATION forming part of Letters Patent No. 595,874, dated December 21, 1897.

Application filed February 18, 1892. Serial No. 421,925. (No model.)

To all whom it may concern:

Be it known that I, AUGUSTUS L. DUWE-
LIUS, a citizen of the United States, residing
in Cincinnati, in the county of Hamilton and
5 State of Ohio, have invented certain new and
useful Improvements in Electric Elevators,
of which the following is a specification.

It is well known that the power required to
start a weight from a condition of rest into
10 motion is much greater than that needed to
maintain the movement when once started.
This law has special significance in connec-
tion with motors of electrically-driven eleva-
tors. With other kinds of motive power over-
15 loading only prevents the starting of the en-
gine, while with the ordinary electric motor
the effect is to burn it out and disable it. A
like effect is produced by the accidental stop-
page of the elevator by obstructions in the
20 hatchway or otherwise. To prevent a waste
of current the motor should be energized in
starting before the brake is released and dis-
connected from the line-circuit in stopping
before the brake is applied. This necessi-
25 tates the construction of a switch or control-
ling apparatus which has the abnormal func-
tion of being first on and first off with rela-
tion to the brake. The frequent use of the
switch incident to elevator service also re-
30 quires special construction to prevent dele-
terious arcing and sparking. When a compara-
tively high speed is attained, the difficulties
of stopping readily and smoothly—that is,
without jar or shock—and accurately with the
35 landings increases with the speed. In elec-
tric elevators as generally constructed coun-
ter-shafting or spur, worm, or other gearing is
interposed between the motor and the hoist-
ing-cable, involving complication of parts
40 loss of power, limitation of speed, and lack
of smoothness in operation, due to the jarring
of gears.

The type of electric motor in use for eleva-
tor purposes requires in starting the manipu-
45 lation of a switch to energize the field-mag-
net and of a rheostat to allow the rotation of
the armature to generate sufficient counter
electromotive force to prevent an excessive
influx of current, and the consequent undue
50 heating of the conductors, destruction of the
insulation, and disabling of the motor. The
manipulation of the rheostat requires care,

skill, and judgment upon the part of the op-
erator, and any failure in either of these is
likely to result disastrously. In attempts to 55
use the ordinary electric motor in a service
to which it is not adapted it has been the
practice to allow the motor to run continu-
ously, or to maintain a current through the
field-magnet coils constantly during business 60
hours, or to start the motor by the use of a
switch and rheostat and then start the eleva-
tor. In stopping, the manipulation is in the re-
verse order, leaving the current on until after
the cab has stopped and involving an element 65
of uncertainty as to the cutting off of the cur-
rent. These methods entail a waste of elec-
tric current and loss of time and interfere
with the practical operation of the elevator.
To protect the motors employed in this serv- 70
ice recourse is had to the insertion in the
line-circuit of a section of fusible wire, the
duplication of which is a matter of extreme
uncertainty, as it is necessarily destroyed in
testing, and it does not furnish the absolute 75
protection required. When by chance of the
proper size to protect the motor, its fusing re-
quires the substitution of another, the ele-
vator in the meantime being disabled. To
avoid the inconvenience and annoyance of 80
frequent substitution of fuses the tendency
is to use large fuses, the result of which is
that it has become an aphorism that a fuse-
protected motor eventually burns out in this
service. 85

One portion of my invention relates more
specifically to the type of elevators known as
“sheave-driven,” in which the power is trans-
mitted to the hoisting-cable through its en-
gagement with a portion of the periphery of 90
a driving-sheave as distinguished from the
drum-driven elevator, in which the hoisting-
rope is attached to or wound about the pe-
riphery of a winding-drum. Among the in-
herent advantages of the former over the lat- 95
ter type may be mentioned the impossibility
of unwinding the hoisting-rope faster than
the car descends and the avoidance of all dan-
ger of overrunning into the upper works.
This is due to the fact that when either the 100
car or the counterweight encounter obstacles
in their descent or reach the bottom of the
hatchway the engagement between the sheave
and hoisting-rope is lessened sufficiently to

prevent the continued transmission of power and movement to the hoisting-rope in the event of carelessness or impossibility of stopping the motor. Another advantage of this system is its special adaptability to the long range of travel demanded in the tall buildings now being erected. As the hoisting-rope merely passes from one side of the driving-sheave to the other, any increase in the height of buildings and consequent length of travel of the elevator-car merely involves an increase in the length of the hoisting-rope, while with the drum-driven elevator serious practical difficulties are encountered in attempts to provide drums of sufficient capacity to wind and stow the long ropes incident to elevators of great range of travel. This is due to the peculiar conditions surrounding elevator-hatchways.

Owing to the nature of the service required of elevator-ropes they are composed of wires made of the softest iron obtainable and frequently annealed during the process of drawing to insure pliability.

To secure the degree of engagement between the driving-sheave and hoisting-rope necessary to transmit the power to the elevator-car, it has been the practice to provide the driving-sheaves with grooves having two sides at an acute angle and resembling the letter V. The wedging of the hoisting-rope in the groove, if sufficiently acute, insured the transmission of the motive power. The immediate effect of this upon the soft-iron rope employed was to pinch it out of shape, causing a change in the molecular structure of the wires, followed by the frictional wear to the outside of the rope incident to its repeated wedging in and release from the groove and its final destruction within so short a service as to render its employment in this manner both unprofitable and dangerous. This was due to the pinch in the V-groove and the pressure resulting from the combined weight of the car with its load and the counterweight. Attempts to dispense with the V-grooves and the consequent wedging and pinching of the rope by substituting elastic fillings in non-wedging grooves were rendered prohibitive by the great strain on the hoisting-rope directly sustaining the weight of its car and counterweight. In order to obviate the premature destruction of the rope and to render this otherwise desirable method of transmission practically and commercially successful, I employ an arrangement of the hoisting-rope by which the pressure of engagement between it and the driving-sheave and the tensile strain of and power transmitted to the rope at this point represent but a fraction of the combined weight of the car and counterweight, this fraction being capable of regulation to keep the pressure strains and power transmission at the point of engagement with the sheave within practical working limits to

insure greatest longevity of the rope, the engagement being frictional as distinguished from gripping.

The object of my invention is to provide means for obtaining higher speed and higher speed relatively to the motive power, means for producing a comparatively powerful torque or pull to overcome the inertia incident to starting an elevator, means for automatically regulating and limiting the quantity of current received by the motor to protect it from burning out and thereby reducing the possibility of error on the part of the operator to the minimum, means for electrically arresting the movement of the elevator without jar or shock, means for electrically regulating the speed of an elevator moved by gravity without the consumption of line-current, means for breaking the electric circuit to protect the motor in the event of accident to the regulating and limiting device, means for reconnecting the circuit by the manipulation of the shifting cable, and to provide mechanism whereby the lifting capacity of the elevator may be increased without increasing the strain or wear upon the cable or bearings or increasing the travel of the counterweight. These objects I can accomplish partly by supplying novel instrumentalities adapted to perform specific functions and partly by the combination and arrangement of the coacting parts; and the invention consists in the instrumentalities and combination and arrangement of instrumentalities hereinafter described and claimed.

In the drawings, Figure 1 is a front view showing an elevator-hatchway, the cage or cab, an electric motor, and the connections between the motor and the cab; Fig. 2, a diagrammatic view illustrating the power-multiplying mechanism; Fig. 3, a top view of the field-coil section short-circuiting terminals; Fig. 4, a side view of the governor employed for regulating the strength of field; Fig. 5, a view of the same at right angles to the position shown in Fig. 4; Fig. 6, a front view of a preferred form of circuit-breaking mechanism; Fig. 7, a front view of a switch or commutator; Fig. 8, a side view of the same; Fig. 9, a diagrammatic view showing the terminals and connections of a series motor adapted to be converted into a series dynamo on closed circuit; Fig. 10, a plan view of the switch-contact terminals. Fig. 11 illustrates the positions of the switch for starting, reversing, and stopping the elevator. Fig. 12 is a diagrammatic view illustrating the electrical connections; Fig. 13, a perspective view showing the relative positions of the brake and switch.

A represents the hatchway of an elevator; B, the cage, platform, or car, hereinafter called the "cab," and C an electric motor having a shaft c, upon which is a sheave or other power-transmitting device c'.

D is a cable the ends of which are represented as fastened to the superstructure at a and a' .

E is a counterweight provided with a sheave e , adapted to travel upon the cable. The cable in the arrangement shown in Fig. 1 takes under a sheave b upon the elevator-cab, over a sheave or sheaves a^2 on the superstructure, under the sheave c' on the motor-shaft, over a sheave or sheaves a^3 on the superstructure, under the sheave e , which carries the counterweight, and thence to its point of attachment.

It will be observed that with the connections illustrated in Fig. 1 the motor has a leverage of two to one in its favor. In Fig. 2 I have illustrated the method of making the connections so applied as to give the motor a leverage of four to one. In this instance the cable takes under a sheave b on the cab, over a sheave c^2 on the superstructure, under another sheave b' on the cab, over sheave a^4 , under the sheave c' on the elevator-shaft, over a sheave a^5 , again under the sheave c' , over a sheave or sheaves a^3 , under the sheave e on the counterweight, over a sheave a^6 on the superstructure, under another sheave e' on the counterweight, and thence to its point of attachment. It will be seen that the counterweight and cab are rigged alike with reference to the cable. By following the same general plan the leverage of the motor may be increased to any required extent. While I have illustrated the hoisting-cable with fixed points of attachment, this is by no means essential, as the same result may be obtained in other ways. In either case the ends of the cable should be at the points where the rate of its travel is the slowest. This plan of construction permits a direct engagement of the hoisting-cable with the drum or drums on the motor-shaft, eliminates the usual interposed gearing and jarring incident thereto, avoids the great waste of power due to the gearing, and permits the accommodation of the speed and torque of the motor to the required speed and power of the elevator. Instead of an auxiliary or separately-constructed rheostat or starting-box or supplementary or additional field-coils I provide the field-coils with sectional or short-circuiting terminals c^3 , brought preferably to the top of the motor.

F is a governor consisting of a shaft f , adapted to rotate with the armature and carrying sector-shaped weights f' , illustrated as centrally pivoted, the opposite ends being of quadrant form. These weights are pivoted, preferably, to a carrier f^2 (which may be integral with the shaft) in such manner that they are free to be moved by centrifugal force from their position of rest until their centers of mass meet at a line through their pivotal points and at right angles to the shaft. The motion of the weights is transmitted through the medium of links f^3 to an equalizer f^4 ,

mounted upon an end-thrust f^5 , guided in carrier f^2 . The end-thrust impinges upon and actuates a lever G , fulcrumed at g . The weights may be returned to their position of rest by springs f^6 or their equivalent. By this means I secure a relatively heavy or low-speed governor, which is prompt to act at low speeds, without developing excessive power at high speeds, as distinguished from the ordinary centrifugal governor, which is designed to perform its functions when attaining an excessive speed.

To one end of lever G is attached a stem g' , carrying at its free end contact-plates g^2 , adapted to engage with the short-circuiting terminals of the field-coil section. When the elevator is at rest, the stem occupies such a position as to leave the contact-plates g^2 out of engagement with the short-circuiting terminals c^3 , in which it is preferably held by a spring g^3 . The governor is arranged to be actuated by the rotation of the armature of the motor, and when actuated forces the lever G and stem g' outwardly. This movement brings the contact-plates g^2 into engagement successively with the terminals c^3 of each of the field-coil sections, thereby short-circuiting them and weakening the field. The action of the governor continues to force the stem g' outward until the normal maximum speed of the motor is attained, the contact-plates being so placed that when this speed is attained any predetermined number of field-coil sections will be short-circuited. If for any reason the motor should attain a speed greater than the predetermined maximum, the action of the governor through the lever and the stem draws the contact-plates still farther, thereby successively breaking the connection between the short-circuiting terminals and increasing the strength of the field and consequently the counter electromotive force and reducing the speed of the motor. The purpose and effect of this construction is to decrease the strength of the field in the direct ratio of the generation of counter electromotive force in the motor and to utilize for power purposes the current ordinarily wasted in the resistance-coils.

H, Figs. 7 and 8, is an electric commutator or switch consisting of a series of plates h , preferably in the form of sectors, arranged in parallel planes and constituting electric contact-terminals.

I is a rocker-shaft connected with and adapted to be actuated by the shifting cable or its equivalent. Upon the rock-shaft, but separated therefrom by a fixed insulating bushing h' , is a carrier h^2 , so mounted as to be capable of partial rotation upon the bushing. This carrier is preferably mounted in such manner that it may be clamped to its bushing with a greater or less degree of pressure. In the form shown it is divided longitudinally to form a split bearing, which is made adjustable by a bolt h^3 . The pressure

is rendered by an interposed spring h^4 . In one end of the carrier is mounted an insulated rocking beam h^5 , hereinafter called the "working beam," provided at its ends with a series 5 of contact-closers h^6 , adapted to make and break electrical connection between the various contact-terminals h .

Secured to and actuated by the rocker-shaft I is a crank-arm h^7 , adapted to engage 10 with and actuate a crank-arm h^8 , secured to the trunnion of the working beam. In the crank-arm h^7 is a slot h^9 , taking over a pin 15 h^{10} , projecting from the carrier h^2 . It will be seen that with the parts in the position shown in Fig. 7 the initial movement of the controlling-cable, acting through shaft I, will move the crank-arm h^7 , thereby moving crank-arm h^8 and working beam h^5 . Movement of the 20 working beam in either direction brings one series of the contact-closers h^6 into engagement with certain of the contact-terminals, thereby making predetermined electrical connections. During this initial movement the carrier, being clamped to the bushing h^1 with 25 sufficient pressure to hold it against rotation until positively driven by engagement with the wall of slot h^9 , remains stationary. After the pin h^{10} engages with the wall of slot h^9 the motion of the shaft I is imparted through 30 crank-arm h^7 and pin h^{10} to the carrier, the combination of electrical contacts made by the initial movement being maintained. This permits the shifting cable to perform subsequent work, such as manipulation of the 35 elevator-brake. The brake may be of any approved type; but I have shown a brake consisting of a friction-wheel c^8 , secured to the armature-shaft, a strap c^7 , taking over the friction-wheel and secured to a lever c^{13} , carrying a weight c^{14} . Extending from the lever 40 is a pin c^{15} , adapted to ride on a cam i' on the rock-shaft. In the position shown the motor is serving as a dynamo, having just been disconnected from the line-circuit, and to apply 45 the brake the rotation of the rock-shaft I must be continued in the direction indicated by the arrow until pin c^{15} drops into a recess i^2 in the cam i' . The weight c^{14} then depresses the lever c^{13} and holds the strap c^7 in 50 contact with the friction-wheel c^8 . The reverse movement of the shaft I first breaks the existing electrical connections, then brings the other series of contact-closers into electrical connection with another set of contact- 55 terminals, and afterward performs the required mechanical functions. In other words, the movement of the shifting cable in either direction first effects the necessary electrical combinations and then performs the necessary mechanical functions.

Fig. 9 illustrates in diagrammatic form the terminals and connections of the motor, the terminals being numbered from 1 to 8. Fig. 10 shows the switch-contact terminals in plan, 60 the dotted lines representing possible switch connections. Fig. 11 shows in diagrammatic form the four positions of the switch serving

in this arrangement to start, stop, reverse, and stop the elevator. Fig. 12 illustrates in diagrammatic form the electrical connections. In these figures, L represents the field-coils, and M a rheostat adjustable in the ordinary way and variable by the action of the shifting cable. This rheostat may be connected directly with shaft I. The letters a , 70 b , c , and d , opposite parts of Figs. 9, 10, 11, and 12, represent corresponding electrical conditions in the motor, switch-contacts, and position of switch. The terminals in Figs. 10 and 12 are numbered to correspond with 75 those in Fig. 9. Of these figures, 1 and 2 denote the line-terminals, 3 and 4 the field-coil terminals, 5 and 6 the armature-terminals, and 80 7 and 8 the terminals for making a short circuit, including the motor then serving as a dynamo. Condition a represents the elevator at rest, with the motor connected as a dynamo and disconnected from the supply-circuit. Condition b may be taken as representing the ascending movement of the elevator, the motor being connected with the supply-circuit. 85 Condition c represents the reverse movement of the elevator, the motor being still connected with the supply-circuit, but having its armature-terminals reversed with reference to condition b . Condition d represents the stopping of the elevator, the supply-circuit having been 90 cut out and the motor converted into a dynamo driven by the elevator on a closed circuit of greater or less resistance. To 95 ascend, recourse is had by means of the switch to condition b , which corresponds with condition d , except that the armature-terminals are reversed. When it is desired to have the 100 preponderance of weight at all times in the elevator-cab and use electric power only for hoisting the cab, the conditions a , b , and d may be used, condition a being used to regulate the descent by gravity of the cab, requiring it to perform work by driving the 105 motor as a dynamo and causing it to generate current through a circuit closed on a greater or less resistance M, variable by the shifting mechanism.

J is an eccentric preferably on an extension 115 of shaft I, adapted to be actuated by the shifting cable j , mounted over sheaves in such manner as to be operated from the cab and serving to limit the play of lever G, thereby preventing the action of the governor beyond 120 a fixed limit and permitting its increase by the operator and enabling him to decrease the normal speed of the elevator.

In Fig. 6 I have illustrated an electromagnetic circuit-breaker.

K represents a supporting-plate, k a magnet, and k' its armature. The armature carries a hooked contact-arm k^2 , adapted to engage with and normally hold against the stress of its spring a spring-actuated contact-arm k^3 . 130 One end of the magnet-coil wire terminates in a binding-post k^4 for connection with the line-circuit, while the other end is fastened to a metallic frame k^5 in electrical connection

with the arm k^2 , which is normally in like connection with the spring-actuated arm k^3 , which is in turn connected with the binding-post k^6 for connection to the motor-circuit.

- 5 A spring k^7 or its equivalent is attached to the arm k^2 and by means of a regulating-screw k^8 with the base of the apparatus. This spring serves to hold the hooked arm k^2 against the pressure of the armature, and the 10 degree of magnetic force required to actuate the armature and thereby disengage the arm k^2 from arm k^3 may be regulated by changing the tension of the spring. The effect of this arrangement is to protect the motor by automatically breaking the supply-circuit when the supply of current tending to actuate the magnet reaches the predetermined limit to be received by the motor and required to overcome the stress of the spring. For the 15 purpose of reconnecting the arms k^2 and k^3 after the operating-switch has disconnected the motor from the supply-line I employ a rock-shaft (preferably rock-shaft I) connected with the shifting cable and provided 20 with a cam i , adapted to engage with and actuate a cam k^9 , which in turn actuates a pendulum-lever k^{10} , having a roller k^{11} at its lower end adapted to engage with and actuate arm k^2 against the stress of its spring, 25 thereby restoring it to its normal position and reconnecting electrically the arms k^2 and k^3 .

The operation of the shifting cable will actuate the swinging lever whether the circuit-breaker is set or not, and the swinging lever 30 is preferably so mounted as to cause a slight movement of the spring-pressed arm k^3 upon its point of contact with arm k^2 , thereby keeping the contacts free from any substances which might tend to impair the electrical connections.

I claim—

1. The combination with a constant-potential line-circuit of a series motor, an electric switch adapted to disconnect the line-circuit 45 and close an independent circuit including the armature in series with a field of variable magnetic strength, thereby converting the motor into a self-excited generator adapted to be driven by the movement of the elevator, substantially as and for the purpose set forth.

2. In an electric elevator, the combination with the motor, of an electric switch adapted to disconnect the motor from the line-circuit, 55 and substitute connections which complete an independent circuit, including the armature in series with a field of variable magnetic strength controlled by the shifting cable or its equivalent, adapted to retard the movement of the elevator, substantially as and for the purpose set forth.

3. The combination with an electric elevator, of an electric switch controlled by the shifting cable or its equivalent, and provided 60 with circuit-closing contacts adapted to alternately make or break electrical connections by the initial portion of the direct or reverse

movement of the shifting cable and maintain the makes or breaks during the continued movement of the shifting cable, substantially as and for the purpose specified.

4. The combination in an electric elevator of a shifting cable, a connection between the cable and a switch adapted to make or break the required connections and a connection 75 between the cable and the elevator-brake whereby the brake is applied after the electrical connections are broken or released after the electrical connections are made, substantially as and for the purpose specified. 80

5. The combination with an electric elevator of a rock-shaft adapted to be actuated by the shifting cable or its equivalent, a working beam intermediately connected with and adapted to be rocked by the rock-shaft, a 85 series of plates serving as electric contact-terminals, and a series of contact-closers at the end of the working beam adapted to make and break electric connections between the plates, substantially as and for the purpose specified. 90

6. The combination with an electric elevator of a rock-shaft controlled by the shifting cable, or its equivalent, a carrier movably mounted on a stationary bearing, a working beam pivotally mounted on the carrier, a crank-arm upon the rock-shaft, a second crank-arm extending from the working beam, a rocking connection between the crank-arms, a series of plates serving as contact-terminals 100 for the electrical connections, a series of insulated contact-closers at each end of the working beam adapted to make or break electrical connections between two or more contact-terminals at the initial movement of the 105 rock-shaft, and mechanism whereby the carrier engages with the crank-arm of the rock-shaft after the initial movement, and is moved thereby, substantially as and for the purpose specified. 110

7. The combination with an electric elevator of a rock-shaft controlled by the shifting cable, or its equivalent, a carrier movably mounted on a stationary bearing, a working beam pivotally mounted on the carrier, a 115 crank-arm upon the rock-shaft and a second crank-arm extending from the working beam, a rocking connection between the crank-arms, a series of plates serving as contact-terminals for the electrical connections, a series of insulated contact-closers at each end of the working beam adapted to make or break electrical connections between two or more contact-terminals at the initial movement of the rock-shaft, mechanism whereby the carrier 125 engages with the crank-arm of the rock-shaft after the initial movement and is moved thereby, and a connection between the shifting cable and the elevator-brake whereby the latter is actuated during the subsequent movement 130 of the carrier, substantially as and for the purpose specified.

8. The combination with an electric elevator of a rock-shaft controlled by the shifting

cable, or its equivalent, a carrier movably and adjustably mounted on a stationary bearing, a working beam pivotally mounted on the carrier, a crank-arm upon the rock-shaft, a second crank-arm extending from the working beam, a rocking connection between the crank-arms, a series of plates serving as contact-terminals for the electrical connections, a series of insulated contact-closers at each end of the working beam adapted to make or break electrical connections between two or more contact-terminals at the initial movement of the rock-shaft, mechanism whereby the carrier engages with the crank-arm of the rock-shaft after the initial movement and is moved thereby, and a connection between the shifting cable and the elevator-brake whereby the latter is actuated during the subsequent movement of the carrier, substantially as and for the purpose specified.

9. The combination in an electric elevator of a rock-shaft controlled by the shifting cable, or its equivalent, a fixed insulating-bushing surrounding the rock-shaft, a series of plates adapted to serve as electrical contact-terminals mounted upon the bushing, a carrier movably mounted on the bushing, a working beam pivotally mounted on the carrier, one or more electrical contact-closers at each end of the working beam, a connection between the rock-shaft and the working beam whereby the latter may be rocked by the motion of the rock-shaft, thereby bringing one or more of the contact-closers into engagement with contact-terminals and the carrier during the rocking motion of the working beam, substantially as and for the purpose specified.

10. The combination in an electric elevator of a rock-shaft controlled by the shifting cable, or its equivalent, a fixed insulating-bushing surrounding the rock-shaft, a series of sector-formed plates adapted to serve as electrical contact-terminals mounted upon the bushing, a carrier movably mounted on the bushing, a working beam pivotally mounted on the carrier, one or more electrical contact-closers at each end of the working beam, a connection between the rock-shaft and the working beam whereby the latter may be rocked by the motion of the rock-shaft thereby bringing one or more of the contact-closers into engagement with contact-terminals and the carrier during the rocking motion of the working beam, substantially as and for the purpose specified.

11. The combination with the shifting cable of the rock-shaft I; the insulating-bushing h' , the plates h carried thereby, the carrier h^2 movably mounted on the bushing, the working beam h^5 pivotally mounted on the carrier and carrying contact-closers h^6 , the crank-arm h^7 upon the rock-shaft, the crank-arm h^8 upon the working beam, the slot h^9 and pin h^{10} , substantially as and for the purpose specified.

12. In an electric elevator the combination

of a motor, its field-coils provided with sectional short-circuiting terminals, a centrifugal governor actuated by the rotation of the armature-shaft and adapted to electrically connect the sectional short-circuiting terminals of the field-coils before and until the armature-shaft shall have attained its normal speed, and to electrically disconnect the same when the armature-shaft exceeds its normal speed, substantially as and for the purpose set forth.

13. In an electric elevator the combination of a motor having its field-coils provided with short-circuiting terminals, a governor actuated by the rotation of the armature-shaft, a lever actuated by the governor, and contact-plates actuated by the lever and adapted to electrically connect the sectional short-circuiting terminals of the field-coils before and until the armature-shaft has attained its normal speed, and to electrically disconnect the same when the armature-shaft exceeds the normal speed, substantially as and for the purpose set forth.

14. A field-magnet governor for electric elevators consisting of a shaft, a carrier mounted thereon, weights of sector form pivoted to the carrier, an end-thrust guided by the carrier, 95 an equalizer thereon and a connection between the equalizer and each of the weights, substantially as and for the purpose specified.

15. A field-magnet governor for electric elevators consisting of a shaft, a carrier mounted thereon, weights of double-sector form pivoted to the carrier, an end-thrust guided by the carrier, an equalizer thereon and a connection between the equalizer and each of the weights, substantially as and for the purpose specified.

16. In an electric elevator, the field-magnet governor F, consisting of shaft f^2 , the weights f^1 pivotally mounted thereon, the end-thrust f^3 , the equalizer f^4 , the links f^5 and the springs f^6 , or their equivalent, combined and arranged substantially as and for the purpose specified.

17. In an electric elevator, the combination with line-circuit terminals, of an electric motor for driving the elevator cab or cage, said motor having its field-coils and armature-coils in series with each other, an adjustable rheostat, and circuit-controlling devices operable from the elevator-cage and adapted to connect the field-coils and armature-coils in series with each other and to the line-circuit terminals and to cut out the rheostat, or to disconnect the field-coils and armature-coils from the line-circuit terminals and include said field-coils and armature-coils in series with each other and the rheostat in an independent circuit; substantially as and for the purpose set forth.

18. In an electric elevator, the combination with line-circuit terminals, of an electric motor for driving the elevator cab or cage, said motor having terminals for its field-coils, and separate terminals for its armature-coils, an adjustable rheostat and circuit-controlling

devices operable from the elevator-cage and adapted to connect the field-coils and armature-coils in series with each other to the line-circuit terminals, and cut out the rheostat, or 5 to disconnect the field-coils and armature-coils from the line-circuit terminals, reverse the direction of current-flow in the armature-coils and include said field-coils and armature-coils in series with each other and with 10 the adjustable rheostat in an independent circuit; substantially as and for the purpose set forth.

19. In an electric elevator, the combination with a series motor, of substantially non-retarding multiplying-rigging connecting said motor to the elevator-cab, whereby the load imposed upon the motor during ascent is substantially that of the cab and its contents only, and an electric switch adapted to disconnect the line-circuit and close an independent circuit including the armature in series with a field of variable magnetic strength, whereby the necessary retardation for the cab on its descent is furnished by converting the 25 motor into a self-excited generator adapted to be driven by the descent of the elevator; substantially as and for the purpose set forth.

20. The combination with an electric elevator-cab, of an electric motor therefor, and non-retarding rigging between the cab and electric motor, said rigging being operated directly from the latter; substantially as and for the purpose set forth.

21. The combination in an electric elevator 35 of an electric motor, an electric switch adapted to break the line-circuit and close a circuit, including the motor, thereby converting the motor into a dynamo, adapted to be driven by the movement of the elevator, with rigging adapted to multiply the power, substantially as and for the purpose set forth.

22. The combination in an electric elevator of an electric motor, an electric switch adapted to break the line-circuit and close a circuit, 45 including the motor, thereby converting the motor into a dynamo, adapted to be driven by the movement of the elevator, with a hoisting-cable and a counterweight carried thereby, and arranged to travel relatively thereto, substantially as and for the purpose set forth.

23. The combination in an electric elevator of an electric motor, an electric switch adapted to break the line-circuit and close a circuit, including the motor, thereby converting the 55 motor into a dynamo, adapted to be driven by the movement of the elevator with a hoisting-cable engaging with a sheave or other power-transmitting device on the motor-shaft, and taking under a sheave on the cab, and a counterweight carried by the cable and traveling relatively thereto, substantially as specified.

24. The combination in an electric elevator of an electric motor, an electric switch adapted to break the line-circuit and close a circuit, 65 including the motor, thereby converting the motor into a dynamo, adapted to be driven by the movement of the elevator, with a motor-

shaft, a sheave or other power-transmitting device thereon, one or more sheaves on the superstructure, a sheave on the cab, a hoisting-cable, and a counterweight carried by the cable and traveling relatively thereto, arranged and operating substantially as and for the purpose specified. 70

25. The combination in an electric elevator 75 of an electric motor, an electric switch adapted to break the line-circuit and close a circuit, including the motor, thereby converting the motor into a dynamo, adapted to be driven by the movement of the elevator, with a sheave 80 or other power-transmitting device, two or more sheaves on the cab, a counterweight provided with two or more sheaves and a hoisting-cable arranged to engage the transmitting device on the motor-shaft and to engage the 85 sheaves on the cab and counterweight, substantially as and for the purpose specified.

26. The combination with an electric elevator of an electromagnetic circuit-breaker adapted to break the line-circuit when the 90 supply of current exceeds the predetermined limit, a swinging lever adapted to reset the switch, a rock-shaft adapted to be actuated by the shifting cable or its equivalent, and a cam upon the rock-shaft adapted to actuate 95 the swinging lever, substantially as and for the purpose specified.

27. The combination with an electric elevator of an electromagnetic circuit-breaker consisting of a magnet in electrical connection 100 with the line-circuit, a contact-arm carried by the armature of the magnet, a second contact-arm electrically connected with the line-circuit and normally in contact with the arm carried by the armature, but adapted to be 105 disengaged by the movement of the armature, a swinging lever adapted to engage with the second arm and restore it to its normal position, a rock-shaft adapted to be actuated by the shifting cable or its equivalent, and a cam 110 on the rock-shaft adapted to actuate the swinging lever, substantially as and for the purpose specified.

28. The combination with an electric elevator of an electromagnetic circuit-breaker 115 consisting of a magnet in electrical connection with the line-circuit, a contact-arm carried by the armature of the magnet, a second contact-arm electrically connected with the line-circuit and normally in contact with the arm carried by the armature, but adapted to be disengaged by the movement of the armature, a swinging lever adapted to engage with the second arm and restore it to its normal position, a rock-shaft adapted to be actuated by 120 the shifting cable or its equivalent, a cam on the rock-shaft, and a cam actuated thereby adapted to actuate the swinging lever, substantially as and for the purpose specified. 125

AUGUSTUS L. DUWELIUS.
